UNITED STATES PATENT OFFICE.

CHARLES E. PETERSON, OF BROOKLYN, NEW YORK, ASSIGNOR TO MICHIGAN MOTOR SPECIALTIES COMPANY, OF DETROIT, MICHIGAN, A CORPORATION OF MICHIGAN.

SPARK-PLUG.

1,052,170.

Specification of Letters Patent.

Patented Feb. 4, 1913.

Application filed January 28, 1908. Serial No. 413,000.

To all whom it may concern:

Be it known that I, CHARLES E. PETERSON, a citizen of the United States, residing at Brooklyn, in the county of Kings and State of New York, have invented new and useful Improvements in Spark-Plugs, of which the following is a specification.

My invention relates to spark plugs and particularly to the manner of binding the insulation between the insulated terminal and the body of the plug.

The improvement has for its object, the simplification of the construction of the spark plug.

Generally stated, the invention consists of the novel devices and combinations of devices hereinafter described and defined in the claims.

In the accompanying drawings which illustrate the invention, like characters indicate like parts throughout the several views.

Referring to the drawings; Figure 1, is a transverse, vertical section, in elevation, (taken approximately on the line $x^1 x^1$ of Fig. 2), showing a spark plug embodying my invention. Fig. 2 is a plan view of the spark plug shown in Fig. 1, some parts being broken away and some parts being sectioned approximately on the line $x^2 x^2$ of Fig. 1.

In the views shown in Figs. 1 and 2, the numeral 1 indicates the body or shell of the plug, which as commonly constructed is of metal, shell-like in form and threaded externally, thus being adapted to be screwed into an engine cylinder. This shell 1 has a shoulder 2 projecting internally as an offset and extending completely around the interior of the shell. A point 3 of metal projecting outward from the shell, downwardly, constitutes one of the sparking terminals. The other spark terminal is carried by the insulator 4, which prevents electrical communication between the electrodes except through the spark gap. This insulator is constructed of porcelain, lava, stone or any other refractory and insulating material. A shoulder 5 formed in the insulator 4 and surrounding it externally, is adapted to rest against the shoulder 2 of the shell 1, when said insulator is inserted from below into the shell in assembling. The insulator 4 has grooves 6 formed in its surface and extending around it. It will be seen that there is a space between the insulator 4 and the

shell 1 opposite the grooves 6. This space in assembling is filled with asbestos packing or any other suitable material 7. This asbestos or packing 7 is pressed firmly in between the shell 1 and insulator 4, and firmly held in place by a steel or other suitable washer 8, slipped down upon the insulator 4. This washer 8 internally just fits upon the insulator 4 and externally just fits into the upper open end of the shell 1. Thus when the asbestos is pressed down and the washer 8 is pressed down upon it, the asbestos will be pressed into the grooves 6 in the insulator 4 and the insulator 4 will be held firmly in place. To hold the washer in place, pressed against the asbestos between the shell 1 and insulator 4, the upper edge 9 of the shell 1 is turned over inwardly upon the washer 8 as shown.

It is important to note, that in place of the grooves 6 in the insulator 4, there may be any raised projection or fillet or any unevenness in the surface of the insulator 4, such that the packing between the shell 1 and insulator 4 may be pressed around or into this unevenness in the surface of the insulator. The object of this unevenness being to enable the insulator 4 to be held by the packing between it and the shell 1, it matters not of what nature this unevenness is, so long as through it the packing will retain a firm hold upon the insulator.

The insulator 4 as usual, bears a spindle 10, having a head 11, at its lower end, which holds the metal washer 12 in place upon the lower end of the insulator 4. This washer 12 forms the spark terminal, between which and the spark point 3 there is a gap, over which the spark is formed. The spindle 10 is threaded at its upper end, to receive a lock-nut 13 which holds the spindle firmly in the insulator 4. A thumb-nut 14 is adapted to be screwed upon the spindle 10 over the lock-nut 13. Between the lock-nut 13 and thumb-nut 14, the conductor 15, connected to the battery or other source of current is held. The other terminal from the source of current as customary is grounded upon the engine and thus connects with the shell 1.

It is important to note that the collar or shoulder 5 in the insulator 4 is adapted to coöperate with the shoulder 2 in the shell 1, that is, the shoulder 5 presses outwardly against the shoulder 2 in the shell, thereby

preventing the insulator from being forced upward in the shell 1. Therefore in assembling the plug the insulator 4 is inserted from the bottom, upward into the shell 1, 5 until the shoulder 2 in the shell prevents further upward motion by its interaction with the shoulder 3 in the insulator 4. While the insulator 4 is held in position with respect to the shell 1, the packing 7 is 10 then forced into place, coöperating with the depressions in the insulator 4 to prevent the insulator 4 from slipping downward from its fixed position upward against the shoulder in the shell 1.

15 What I claim is;

1. In a spark plug, a shell and an insulator; the shell having an internal shoulder surrounding the insulator and the insulator having a collar and having a rugged or uneven surface adjacent to said collar, said collar coöperating with the shoulder in the surrounding shell, in combination with a packing between the insulator and the shell adapted to grip the rugged or uneven surface of the insulator, substantially as described.

2. In a spark plug, a shell and an insulator; the shell having an internal shoulder surrounding the insulator and the insulator having a collar and having a groove or grooves adjacent to said collar, said collar coöperating with the shoulder in the surrounding shell, in combination with a packing between the insulator and the shell adapted to coöperate with the groove or grooves in the insulator, to hold the insulator, substantially as described.

3. In a spark plug, a shell and an insulator; the shell having an internal shoulder surrounding the insulator and the insulator having a collar and having a rugged or uneven surface adjacent to said collar, said collar coöperating with the shoulder in the surrounding shell, in combination with a packing between the insulator and the surrounding shell adapted to grip the rugged or uneven surface of the insulator, and a washer upon the insulator above the packing, the edges of the shell being turned upon 50 the washer, to hold it against the packing, substantially as described.

4. In a spark plug, a shell and an insula-

tor; the shell having an internal shoulder surrounding the insulator and the insulator having a collar and having a rugged or uneven surface adjacent to said collar, said collar coöperating with the shoulder in the surrounding shell, in combination with a packing between the insulator and the shell adapted to grip the rugged or uneven surface of the insulator, the edges of the shell being turned upon the packing, substantially as described.

5. In a spark plug, a holding shell and an insulator; the shell having an internal collar surrounding the insulator and the insulator having a collar bearing outwardly against the collar in the holding shell, said insulator having a rugged or uneven surface adjacent to said collar, in combination with a packing between the insulator and the shell adapted to grip upon said insulator, substantially as described.

6. In a spark plug, a shell and an insulator; the shell having an internal shoulder surrounding the insulator and the insulator having a collar and having depressions in its surface adjacent to the collar, in combination with a packing between the insulator and the shell, the packing being pressed into the depressions in the surface of the insulator to hold the insulator in position in the shell, the collar of the insulator bearing against the shoulder of the shell, substantially as described.

7. In a spark plug, a shell and an insulator; the shell having an internal shoulder surrounding the insulator and the insulator having a collar and having projections in its surface adjacent to the collar, in combination with a packing between the insulator and the shell, the packing being pressed around the projections in the surface of the insulator to hold the insulator in position, the collar of the insulator bearing against the shoulder of the shell, substantially as described.

In witness whereof, I have hereunto set my hand this 27 day of January 1908.

CHARLES E. PETERSON.
